UNITED STATES PATENT OFFICE.

CHARLES W. WARD, OF LAKWOOD, OHIO.

SEMAPHORE-OPERATING MECHANISM.

1,153,739.

Specification of Letters Patent. Patented Sept. 14, 1915.

Application filed February 29, 1912. Serial No. 680,769.

To all whom it may concern:

Be it known that I, CHARLES W. WARD, a citizen of the United States of America, residing at Lakewood, in the county of 5 Cuyahoga and State of Ohio, have invented a certain new and useful Improvement in Semaphore-Operating Mechanism, of which the following is a specification, reference being had therein to the accompanying drawing.

10 My invention relates to mechanisms of the type used for operating semaphore signals, and is devised for the special purpose of operating semaphores in a "normal clear" 15 signaling system. While of this special relation however, I desire it to be understood in the beginning that my invention may be adapted to use in other systems, such as "normal danger" systems without departing in any wise from its generic spirit. Furthermore the character of the semaphore as a signal is also immaterial, inasmuch as any known form of semaphore, or other 20 equivalent device, may be operated by my 25 semaphore operating mechanism.

According to my invention the semaphore arm is biased by gravity or other means to one of its indicating positions, and is moved by suitable motor power to another 30 of its indicating positions, such for instance as "danger" or "clear" positions respectively. The mechanism through which these movements are permitted in the one case and effected in the other is what constitutes my 35 invention. The semaphore arm is biased by gravity to one of its positions and motor driven through a clutch device, a mutilated driving gear, and a pair of pinions driven each in the same direction and engaging said 40 driving gear alternately—to another of its positions. The details of my invention through which these devices are used in the embodiment which I shall describe are made effective in their coöperation to produce 45 the results stated, and will appear more clearly when described in connection with the drawings. Here it may be stated that in so far as the mutilated gear and driving pinions are concerned, any equivalent gear 50 having driving and non-driving parts adapted to be engaged by the driving pinions or equivalent devices may be used in lieu thereof.

55 Referring to the drawings: Figure 1 shows in elevation one form of the mechanism of my invention, and Fig. 2 is a simi-

lar view showing a modification of the form of Fig. 1.

The semaphore arm S is mounted on a semaphore shaft s. Mounted on the shaft s and disconnected therefrom is the driving gear D. This driving gear is provided with abutments on one of its faces in the form of pins p, spaced at regular intervals, and coacting with these abutments p is a catch arm a pivotally supported from magnet frame F as shown, the frame F being rigidly secured to the semaphore shaft s and carrying the clutch magnet m, which, through its armature A, controls the movements of the catch arm a through the catch e connected with the arm a and overlying one end e, (in this case the pivoted or uppermost end) of the armature A. There are two things especially to be noted about this portion of the mechanism of my invention. First the semaphore is adapted to be moved through 90° as clearly shown by Figs. 1 and 2, and the abutments p to this end are spaced by intervals of 120°, intervals greater than 90° by 30°. Secondly the electromagnet m as respects the armature which it carries, is movable from a position in which its armature is biased, in this case by gravity, away from its poles to a position in which said armature is biased toward the poles, independently of magnetic pull. The advantages accruing from these structural features of my invention will readily be apparent when the operation is considered.

The driving gear D is a mutilated gear, the gear having several teeth removed at points equidistant from each other as clearly shown in Fig. 1. Any suitable driving motor R may be used to drive this gear. Driving connection is made with the gear D by means of a centrally fixed driving pinion N, which drives the two pinions N¹ and N² each in the same direction. The driving gear N¹ is fixed in position to engage the teeth of the gear D, while the pinion N² is shiftably mounted, and movable about the axis of the central pinion N into and out of engagement with the gear D. A spring g normally biases the pinion N² toward engaging position. On the shaft s of the semaphore is a sweep lever E adapted to engage the end of the lever l or other equivalent frame on which the pinion N² is mounted and retain the same out of engagement with the gear D when the signal is in one of its two positions. As thus organized, the mecha-

nism of my invention operates with great ease and certainty, and constitutes a mechanism of great sturdiness and durability, each of which qualities is essential under 5 the exacting conditions of service on the rail roads.

In operation, we will assume that the signal has been operated by the motor R to the position shown in Fig. 1. This is the "clear" 10 position. The magnet *m* of the electromagnetic clutch is shown as energized and holding the armature *A* up, thus retaining the catch arm *a* in its clutching or connecting position, and the gear D and with it the 15 semaphore S and the magnet *m* connected with the semaphore shaft *s*, have been rotated clockwise until the pinion *N*¹ has become juxtaposed to a mutilated or non-driving portion of the gear D. At this 20 point the driving motor may have its power supply cut off in any suitable manner, and the semaphore will be held at "clear" owing to the engagement of pinion *N*¹ with the non-driving portion of the gear D. When 25 the signal is desired set at "danger" as is normally the case in the "normal danger" systems, the magnet *m* is deenergized whereupon its armature is drawn by gravity immediately toward the vertical position shown 30 in dotted lines in Fig. 1. The catch arm *a* is therefore released and the semaphore arm S falls 90° to the "danger" position by virtue of the force exerted on the weight *W*, although the weight of the semaphore arm alone may be made sufficient for this purpose. The gear D during this time remains 35 stationary, being held locked in this position by the pinions *N*¹ and *N*², the pinion *N*² having been released to engage with the gear D through the counterclockwise movement of the sweep E. The positions of the 40 parts are shown in dotted lines in Fig. 1. The magnet *m* has been revolved counterclockwise with the semaphore, and its armature *A*, which was removed from its face 45 upon its deenergization, is now restored to its face by reason of the rotation. In this position the end of the armature *e* engages again with the catch *c* and the catch arm *a* is in position for co-action with one of the 50 abutments *p*. The nearest abutment however is 30° removed from it. If it is desired to move the signal to "clear" the magnet *m* is energized, retaining its armature *A* in 55 position and holding the catch *a* in engaging position, and the motor R is supplied with power. Owing to the presence of the gear *N*¹ juxtaposed to a mutilated portion 60 of the gear, this pinion cannot initiate movement of the driving gear, but the pinion *N*² which engages the driving gear at this time, can and does initiate such movement. The 65 driving gear is moved thereby approximately 30° or less until the catch arm *a* is engaged by one of the abutments *p*, and

then further until the sweep E disengages the pinion *N*² and engages pinion *N*¹ with gear D, the mutilated portion of the gear having at this time passed the gear *N*¹, and still further until the pinion *N*¹ engages 70 the next successive mutilated non-driving portion of the gear D, a total movement of 120°, whereupon motion of the semaphore ceases without shock and the motor R may be cut out. It is especially to 75 be noted in this connection, that the interval between the gears *N*¹ and *N*² is shorter than to any of the intervals between the mutilated portions of the gear D. By reason of this fact, no matter which of the 80 non-driving portions of the gear is engaged by one of the gears *N*¹, the other of the pinions *N*² is always opposite the driving portion of the gear.

The modification of Fig. 2 differs from 85 the form of Fig. 1, first in that the catch arm *a* is connected to the end *e* of the armature by means of a hinged joint. The weight of the armature *A* may be readily insufficient to interfere with the proper passage 90 of the arm *a* by the engaged abutment *p* without hindrance. Secondly the gears *N*¹ and *N*² instead of being mounted one on a fixed frame *L'* and the other on a movable frame *L* are both mounted on a common 95 frame L shiftable about the axis of the central pinion N. The pinions *N*¹ and *N*² are rocked alternately into engagement with the driving gear D, the engagement of the pinion *N*² being effected to initiate engagement 100 after the gear *N*¹ has come to a mutilated portion of the gear D, and the gear *N*¹ being simultaneously removed from its engaging position. A dog *d* prevents backward 105 rotation at any time. A similar dog *d* may be used in connection with the device of Fig. 1 if desired.

While I have described the two best forms of my invention now known to me, I do not desire to be limited to these two forms 110 only. I desire to cover in the annexed claims all forms which my invention may be given without departing from its basic nature.

It is to be noted that my invention is especially adapted for use on a "closed circuit" 115 electrical system, in which the electromagnet *m* or equivalent controlling device is normally energized. In the embodiments disclosed, this would constitute a "normal clear" signaling system, and if current was 120 cut off the line when the signal was at clear, it would immediately drop to "danger" position.

Having thus described my invention, what I claim and desire to secure by Letters Patent is:-

1. A semaphore signal comprising a semaphore, and intermittently operating driving means therefor comprising a gear having driving and non-driving portions, and co- 130

- operating driving elements, each movable to drive said gear in the same direction, and shifting devices for said driving elements, associated with said semaphore and operative when one element is coacting with the non-driving portion of said gear to cause the other driving element to coact with the driving portion of said gear. 55
2. A semaphore signal comprising a semaphore, and intermittently operating driving means therefor comprising a mutilated driving gear, and driving pinions driven each in the same direction and engaging said mutilated gear alternately. 60
- 10 3. A semaphore signal comprising a semaphore, and intermittently operating driving means, comprising a driving gear for the shaft mutilated at intervals, and a pair of driving pinions driven each in the same direction and engaging said mutilated gear alternately at points spaced by an interval unequal to the intervals between the mutilated portions of the said driving gear. 65
- 15 4. A semaphore signal comprising an operating shaft, a semaphore carried by the same and intermittent driving means for the same comprising a mutilated driving gear for the shaft, and a pair of driving pinions driven each in the same direction, one of 70 which is normally fixed in position to engage said driving gear, and the other of which is moved to engage said gear when the said fixed pinion is disengaged by juxtaposition to a mutilated portion of the driving gear. 75
- 20 5. A semaphore signal comprising an operating shaft, a semaphore carried by the same, and intermittent driving means for the same comprising a mutilated driving gear for the shaft, and a pair of driving pinions driven each in the same direction, one of which is normally fixed in position to engage said driving gear, and the other of which is normally out of engaging position and adapted to be moved thereto, and means dependent upon predetermined movements of the semaphore to effect the engagement and disengagement of the movable pinion. 80
- 25 6. A semaphore signal comprising an operating shaft, a semaphore carried by the same, and intermittent driving means for the same comprising a mutilated driving gear for the shaft, and a pair of driving pinions driven each in the same direction, one of which is normally fixed in position to engage said driving gear, and the other of which is normally out of engaging position and adapted to be moved thereto, and means dependent upon predetermined movements of the semaphore to effect the engagement and disengagement of the movable pinion. 85
- 30 7. A semaphore signal comprising an operating shaft, a semaphore carried by the same, and intermittent driving means for the same comprising a mutilated driving gear for the shaft, and a pair of driving pinions driven each in the same direction, a common driving pinion therefor, one of said pinions being fixed in position to engage said driving gear and the other being shiftable about said driving pinion axis into and out of driving engagement with said driving gear, and shifting means dependent for movement on predetermined movements of said semaphore for effecting said engagement of the shiftable gear. 90
- 35 8. A semaphore signal comprising a semaphore, and intermittently operating driving means therefor comprising a mutilated driving gear disconnected from the semaphore, and driving pinions driven each in the same direction and engaging said mutilated gear alternately, and means for controlling the connection of the driving gear with the semaphore. 95
- 40 9. A semaphore signal comprising a semaphore, and intermittently operating driving means therefor comprising a mutilated driving gear, and driving pinions driven each in the same direction and engaging said mutilated gear alternately, regular spaced abutments carried by said driving gear, the intervals between abutments being greater than the effected movement of the semaphore in any instance, and means coacting with said abutments to effect driving connections of said driving gear with said semaphore. 100

In testimony whereof I affix my signature in presence of two witnesses.
